UNITED STATES PATENT OFFICE.

ISAAC HARTER, OF DONGAN HILLS, NEW YORK, ASSIGNOR TO THE BABCOCK & WILCOX COMPANY, OF BAYONNE, NEW JERSEY, A CORPORATION OF NEW JERSEY.

FURNACE.

Application filed December 18, 1918. Serial No. 267,227.

To all whom it may concern:

Be it known that I, ISAAC HARTER, a citizen of the United States, residing at Dongan Hills, in the county of Richmond and State of New York, have invented a new and useful Improvement in Furnaces, of which the following is a specification.

My invention relates to a furnace for a steam boiler and more particularly to an inclined wall for a furnace, and it has for its object the improvement in a device of this character.

An inclined furnace wall is desirable under certain conditions, and particularly when the stoker extends well into the furnace, as does the furnace stoker which I have illustrated, such a construction increasing the volume of the combustion chamber thereby prolonging the period of combustion of the gases therein and promoting the efficiency of the furnace. In accordance with my invention, provision is made for the free expansion and contraction of the inclined wall, thereby avoiding injury to the same and to the parts associated therewith.

My invention will best be understood by reference to the accompanying drawings, in which Fig. 1 is a vertical section through a furnace and the parts associated therewith, embodying my invention; Fig. 2 is a sectional view similar to Fig. 1, but showing a modified form of the lower wall support and illustrating only the inclined wall and the parts directly associated therewith; Fig. 3 is an end elevation partially in section on the line X—X of Fig. 2; Fig. 4 is an inverted plan, partially in section, the view being taken along a horizontal plane passing through the openings of the inclined wall, and Fig. 5 is a rear view of the lower portion of the furnace. Similar reference characters indicate similar parts in the different views of the drawings.

Referring now to the drawings, 10 indicates a bank of inclined water tubes of a steam boiler of the Babcock & Wilcox type, connected at their ends to downtake headers 11 and uptake headers 12, respectively. As here shown, the lower row of tubes 13 is separated from the remaining tubes of the bank to form a space 13^a. Vertical baffles 14 and 15 are provided for directing the gases over the boiler tubes in a plurality of passes, the upper front portion of the combustion space being closed by an inclined

baffle 16 connecting the lower end of the baffle 14 and the top of the front wall 17 of the furnace, the side walls of the furnace being indicated by the character 17^a (see Fig. 4). The stoker 18, which is set well into the furnace, is here shown as being of the underfeed type.

The rear part of the furnace comprises a furnace wall 19, which is here shown as substantially vertical, the same being supported by a framework comprising cross-beams 19^a. The operating floor of the furnace is indicated by the reference numeral 20. An inclined wall 21, which is indicated in general by the reference numeral 21, forms, at its upper end, at 22, a sliding joint with the wall 19, thereby providing for the free expansion and contraction of the inclined wall without injury thereto or to the associated parts. It will be apparent that a wall thus inclined will provide a combustion chamber having a larger volume than would one in which the rear wall extended vertically from the rear end of the stoker. The lower end of the wall 21 is supported on the stoker box 23, the upper wall of which box is provided with steps 24 arranged at substantially right angles to the face of the wall so that the courses 25 of the masonry or brickwork, which are also arranged at substantially right angles to the outer face of the inclined furnace wall, rest against the steps of the upper wall of the stoker box, as best shown in Figs. 1 and 2. This stepped arrangement of the stoker box overcomes any tendency that the bottom of the inclined wall might have to creep toward the stoker side of the furnace, due to the inclination of the wall and to the intermittent expansion and contraction thereof. The steps of the stoker box are air-cooled by means of air obtained from the forced blast system which is used in connection with the underfeed stokers. The dumping-bars 26 of the stoker are in part supported by the box 23. The masonry or brickwork of the inclined wall is laid against and supported by a framework exterior to the wall and comprising end members 27, which extend longitudinally of the inclined wall and which are connected by I-beams 28, which hold in position angle-irons 29 placed against the masonry or brickwork. The lower end of the inclined wall is provided with openings 30 which afford access to the stoker 18 and

105

110

particularly to the dumping-bars thereof, the openings being closed by doors 31.

By providing the inclined wall with an opening adjacent to the dumping bars, it is possible for the operator to stand nearer the dumping bars in removing the clinker than would be the case if the upper vertical section of the wall against which the top of the inclined wall rests were extended downward to the floor line and the opening for access to the dumping bars placed in the vertical wall. The combination, therefore, serves to provide an efficient arrangement for getting at the clinker where a stoker or other grate is set in a position with reference to the boiler similar to that shown in the drawings.

In Fig. 2 I have shown a slight modification of the wall support, which is intended for use in connection with the stoker boxes in common use at the present time, or as a wall support independent of a stoker box. I have indicated a box such as commonly used, by the reference numeral 32, above which is disposed a plurality of stepped plates 33, having flanges 34 extending downwardly behind the box to prevent forward creepage of the bottom of the wall 21. A stepped member continuous along the bottom of the wall may be used if desired. However, by providing a support consisting of a plurality of shorter members spaced at intervals beneath the wall, I avoid any disadvantage that may arise due to the expansion and contraction of an independent support made in one piece. The upper wall of the box 32 is perforated to admit air from the box 32 to the spaces between the upper wall of the box 32 and the plates 33 and thereby cool the latter.

It will be understood that this inclined wall is equally applicable in cases where no stoker air box is supplied under the wall. When the inclined wall is used independent of the stoker parts, the stepped plate or plates may be anchored to a concrete or other foundation and the inclined wall supported thereon. As a cooling means, air may be permitted to circulate through openings in the side walls of the furnace and under the plates. Where no cooling means is required, the said member may, if it is desired, be made of a solid casting.

What I claim and desire to secure by Letters Patent of the United States is:—

1. In a furnace, a furnace wall, a second furnace wall inclined to the first and forming a sliding joint therewith, a support for said inclined wall, said inclined wall being provided with an opening independent of said support for affording access to the interior of the furnace.

2. In a furnace, a furnace wall, a second furnace wall inclined to the first and forming a sliding joint therewith, a support for

holding the bottom of the wall in fixed horizontal relation to said first wall, said inclined wall being provided with an opening independent of said support for affording access to the interior of the furnace. 70

3. In a furnace, a furnace wall, and a second furnace wall inclined to the first wall and resting at its upper end against the side of said first wall and having a sliding joint therewith. 75

4. In a furnace, a furnace wall, and a second furnace wall inclined to the first wall and resting at its upper end against said first wall and having a sliding joint therewith, and a member stepped transversely of 80 said wall for supporting the lower end thereof, the bearing surfaces of said member being substantially at right angles to the face of the wall.

5. In a furnace, a furnace wall, and a second furnace wall inclined to the first wall and resting at its upper end against said first wall and having a sliding joint therewith, and a member stepped transversely of 85 said inclined wall for supporting the lower 90 end thereof.

6. In a furnace, a substantially vertical furnace wall, and a second furnace wall inclined to the first wall and resting at its upper end against the vertical wall and having a sliding joint with the side thereof, supporting means disposed beneath the lower end of the inclined wall and adapted to hold the said lower end of the inclined wall in fixed horizontal relation to the said 100 vertical wall. 95

7. In a furnace, a furnace wall, a second furnace wall inclined to the first wall and resting at its upper end against said first wall and having a sliding joint therewith, 105 and a supporting box beneath the lower end of said inclined wall, the upper side of which is formed with steps transversely of said inclined wall on which the brickwork of the inclined wall has its bearing, 110 said box being formed to admit air for cooling the same.

8. In a furnace, a furnace wall, a second furnace wall inclined to the first wall and resting at its upper end against said first wall and having a sliding joint therewith and a supporting box beneath the lower end of said inclined wall, the upper side of which is formed with steps transversely of 115 said inclined wall on which the brickwork of the inclined wall has its bearing, said box being formed to admit air for cooling the same and constituting a support for the inclined wall. 120

9. In a furnace, a substantially vertical 125 furnace wall, a second wall inclined to the first wall and resting at its upper end against the side of the vertical wall and forming a sliding joint therewith, and a support for holding the bottom of the inclined 130

wall in fixed horizontal relation to the vertical wall.

- 10 10. A foot support for an inclined wall comprising a metallic plate having a stepped 5 upper surface on which the wall rests, the steps extending longitudinally of the wall and parallel to the face thereof, and means to anchor the support against horizontal movement under pressure of the wall.
- 10 11. A foot support for an inclined wall comprising a metallic plate having a stepped upper surface on which the wall rests, the steps extending longitudinally of the wall and parallel to the face thereof, the steps 15 having air spaces beneath them wherein cooling air may be circulated.
12. In combination, an operating floor, a furnace comprising a grate, a rear furnace wall supported sufficiently above said operating floor to afford space beneath said wall for an operator, an inclined furnace wall supported at its upper end against said rear furnace wall and provided with an opening affording access to said grate.
- 25 13. In combination, an operating floor, a furnace comprising a grate having dumping bars at the rear of the furnace, a rear furnace wall supported sufficiently above said operating floor to afford space beneath said wall for an operator, an inclined furnace wall supported at its upper end against said rear furnace wall and provided with an opening affording access to said dumping bars.
- 35 14. In combination, an operating floor, a furnace comprising a grate, a rear furnace wall supported sufficiently above said operating floor to afford space beneath said wall for an operator, an inclined furnace 40 wall having its upper end slidingly seated against said rear furnace wall and provided with an opening affording access to said grate.
15. In combination, a furnace, a grate 45 for a boiler having dumping bars at the rear of said furnace, an inclined rear furnace wall, and a support therefor, said inclined wall having an opening therethrough inde-

pendent of said support to afford access to said dumping bars, and a structure against 50 which the upper end of said inclined wall is slidingly seated.

16. In combination, a furnace, a grate for a boiler having dumping bars at the rear of said furnace, an inclined rear furnace 55 wall and a support therefor, said inclined wall having an opening therethrough independent of said support to afford access to said dumping bars, and a rear furnace wall against which the upper end of said 60 inclined wall is slidingly seated.

17. In a furnace, a rear furnace wall, a grate, an air-cooled supporting member located adjacent to said grate, and an inclined furnace wall seated directly on said supporting member and slidingly seated at its upper end against said rear furnace wall.

18. In a furnace, a furnace wall, a second furnace wall inclined to the first and forming a sliding joint therewith, a supporting framework for said inclined wall located at the rear thereof and itself inclined to the first mentioned wall, the courses of the masonry of the brick work of said inclined wall being arranged at substantially 70 right-angles to the face of the inclined wall.

19. In a furnace, a furnace wall, a second furnace wall inclined to the first and forming a sliding joint therewith, a stepped base 80 supporting member for the inclined wall, a supporting framework for the inclined wall located at the rear thereof and itself inclined to the first mentioned wall, the courses of the masonry of the brick work of the inclined wall being arranged at substantially 85 right-angles to the face of the inclined wall and the bricks of the wall being laid against the steps of said stepped member.

In testimony whereof, I have hereunto 90 signed my name in the presence of two subscribing witnesses.

ISAAC HARTER.
